STRAIN RELIEF FOR ELECTRICAL CONNECTORS

Svend Laessøe Pedersen, Copenhagen, Denmark

Application April 8, 1948, Serial No. 19,782

8 Claims. (Cl. 173—322)

1

This invention relates to electrical connections. In my copending application Serial No. 12,658, filed March 2, 1948, I have disclosed forms of electrical connections for use in plugs and lamp sockets, as well as a wide variety of other types of appliances, by means of which the wire-ends of an electric cord may be easily and safely secured. It is an object of the present invention to provide an even more efficiently-operated and effective arrangement.

Pursuant to the invention there is provided an arrangement into which a cord with free wire-ends may be inserted by a single motion, and the cord clamped and the wires connected by a single additional motion. Pursuant to the invention in certain of its aspects, moreover, there are provided cord-clamping means of such character that outward pull on the cord will tend to increase the clamping action. In various of its specific aspects the invention contemplates the provision of an electrical connection comprising two pivotally-mounted parts having cord-clamping surfaces laterally of the pivot point and wire-clamping and contact-forming surfaces at a point spaced from the pivot point, having a cord-clamping surface eccentric of the pivot-point, and having effective and efficient means to lock the assembly in closed position. In its still more specific aspects it contemplates the provision of means which are simple and inexpensive to manufacture and which may be assembled and disassembled without the use of screws of other difficultly-operable means.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention, reference should be had to the following detailed description taken in connection with the accompanying drawings, in which:

Figure 1 is a perspective view of an electric plug embodying the invention, showing the same in open position;

Fig. 2 is a transverse sectional view along the line 2—2 of Fig. 1, showing the plug in closed position with a cord end clamped therein;

Fig. 3 is a transverse sectional view along the lines 3—3 of Fig. 2;

Fig. 4 is a perspective view of a modified form of arrangement adapted for use with a bulb socket, showing the parts in open position;

2

Fig. 5 is a vertical sectional view of the arrangement of Fig. 4 in closed position and assembled with a socket casing; and

Fig. 6 is a transverse sectional view along the line 6—6 of Fig. 4.

In the form of construction exemplified in Figs. 1-3 there are provided a pair of insulating members 10 and 11 formed, in the present instance, entirely of insulating material and pivotally connected at 12. The member 11 is formed with a main passageway 14 which is divided by a separator 15, which is V-shaped in the present instance, to provide channels 16 and 17 which lead inwardly and laterally thru recesses 20 and 21. At the inner sides of the recesses there are provided resilient contact strips 22 and 23 which in the present instance incline outwardly toward the base of the recesses so as to permit inward resilient movement at this point. The strips 22 and 23 are mounted on stems 24 and 25 which serve as leads connecting the contact strips to the insertable contact arms 26 and 27 of the plug. Notches 28 and 29 are provided in the respective strips 22 and 23 to accommodate the wire ends.

An electric cord 30 with separated insulated conductors 32 and 33 at its end may be readily received by the plug just described. The conductors, with the insulation removed at their wire-ends 34 and 35, may be thrust along the passageway 14 toward the separator 15 which will divide them so that the end 34 will move along the channel 16 into the recess 20 and the end 35 will move along the channel 17 into the recess 21. The member 10 is roughened as at 36 at one side of the passageway 14 and the member 11 is formed with a roughened curved surface 37 at the other side of the passageway 14, this roughened surface 37 being eccentric to the pivot pin 12 so that when the members 10 and

11 are moved apart they will form an opening between the surfaces 36 and 37, and when they are moved together a cord 30 will be gripped firmly therebetween. As will be seen, moreover, any pull on the cord 30 tending to withdraw it from the passageway 14 will, when the assembly 10—11 is closed, serve merely to tend to pull the surface 37 tighter against the surface 36 thus effectively preventing any pull from loosening the connection until the members 10 and 11 are intentionally swung open on the pivot 12. The member 11 carries lugs 38 and 39 adapted to move within the recesses 20 and 21 as the assembly is closed; the inner surface of the lugs being so positioned as to press the wire-ends respectively against the resilient strips 22 and 23. The

forward surfaces of the lugs are recessed as at 40 and 41 to accommodate excess lengths of wire.

As will be appreciated, the face 42 of the member 11 from which the contact arms 26 and 27 project and the alined face 43 of the member 10 provide a seat which is set against the face of a wall socket when the plug is in use. Pursuant to the invention in certain of its more specific aspects the exemplified plug provides a releasable locking means which is accessible only when access can readily be had to this seat. Thus the locking means may not be released except when the plug is removed from the socket. In the present instance this locking means consists of a toothed resilient arm 45 set in the end of the member 11 adapted to snap over a toothed surface 47 in an arm-receiving slot 48. The slot 48 is somewhat longer than the arm 45 to permit a knife or other handy implement to be inserted beyond the end of the arm after the plug has been withdrawn from its socket to pull the arm free.

In the form of construction exemplified in Figs. 4-6 there is provided a lamp socket comprising members 10a and 11a assembled with or providing parts 12a, 14a, 15a, 16a, 17a, 20a, 21a, 22a, 23a, 24a, 25a, 28a, 29a, 36a, 37a, 38a, 39a, 40a, and 41a which are generally similar, respectively, to those parts of the construction of Figures 1-3 which are similarly numbered without subscripts. Instead of the members 26 and 27 a resilient contact piece 50 for the center terminal of an electric bulb is provided on the end of the lead 24a, and a contact piece 51 for the side terminal of the bulb, is provided on the end of the lead 25a.

The member 10a is formed with a ledge 52 and the member 11a with a ledge 53, which are adapted to rest on the rim 54 of a casing member 55 with which a casing member 56 is adapted to be releasably connected as by screw threads 57. The casing members 55 and 56 are preferably formed of insulating plastics, and the casing member 56 is formed with a shoulder 58 adapted to extend over the ledges 52 and 53, and is internally threaded to receive a bulb.

Since certain changes may be made in the above article and different embodiments of the invention could be made without departing from the scope thereof, it is intended that all matter contained in the above description or shown in the accompanying drawing shall be interpreted as illustrative and not in a limiting sense.

I claim:

1. In an electric socket, the combination with an insulating casing including bulb retention means and electric terminals for interconnection to the bulb contacts, of a connecting mechanism, comprising, an insulating base removably mounted in said casing and having an aperture and a surface, an insulating cover for said aperture hinged to said base and being movable about the hinge axis between closure and release positions, respectively, a cam on said cover having a continuous curvature convexly eccentrically of the hinge axis and disposed opposite said surface when said cover is in closure position to squeeze for clamping therebetween an electric cord, and respectively to release the same when said cover is in release position, said cam being in said closure position near dead center, whereby outward pulling on said cord will urge said cover further towards closure, extensions on said terminals positioned on said base, and means on said cam disposed, in said closure position of said cover, adjacent said extensions and operable to

press thereagainst for electric contact the wires of said cord.

2. In an electric socket, as claimed in claim 1, further characterized in that, said surface of said base being curved similar to the curvature of said cam though opposite with respect thereto and concave, whereby an elongated portion of said cord may be gripped throughout therebetween positively while free from cord damage.

3. In an electric socket, as claimed in claim 1, together with, means intermediate said casing and said mechanism operable to maintain said cover in closure position.

4. In an electric socket, as claimed in claim 3, further characterized in that, said casing being composed of at least two parts, and said locking means comprising an annular shoulder formed on said base and said cover and aligned throughout when said cover is in closure position, and upper and lower ring surfaces on said parts of said casing surrounding said shoulder to maintain closure and oppositely supporting it removably against axial movement in either direction for releasable suspension of said mechanism within said casing.

5. In an electric connector, for use with an insulated cord having a plurality of wires, in combination, an insulating body having an aperture and having a cord receiving recess at one end extending inwardly forming on the body interior a continuous curved depression spaced opposite to and positioned concavely eccentrically of the hinge axis, an insulating cover hinged to said body and being movable about said axis between a closure position wherein it is disposed across at least a major part of said aperture, and respectively a release position wherein it is positioned at an angle thereto, said cover comprising a cam having a convex curvature substantially parallel with and positioned opposite to said curved depression in said closure position of said cover for oppositely gripping therebetween an elongated portion of said cord, said cam surface in said closure position being near dead center, whereby an outwardly exerted pulling force on said cord will urge the cam further into gripping position, and all the points of said cam surface being spaced from said hinge axis for a distance smaller than the shortest distance of any point of said curved depression from said hinge axis, whereby said cam may manually be moved between the closure and release positions, said cam in the release position of said cover being spaced from said curved depression and from said recess sufficiently to release said cord, a contact terminal for each wire disposed on said body and protruding to the exterior thereof, means connected to said cover and positioned in said closure position adjacent said terminals to press each wire into contact with a terminal, and means operable for releasably locking said cover in said closure position.

6. In an electric connector, for use with an insulated cord having a plurality of wires, in combination, an insulating body having an aperture and having on the body interior a continuous surface, an insulating cover hinged to said body and being movable about the hinge axis between a closure position and respectively a release position at an angle thereto, said cover comprising a cam having a convex curvature eccentrically of the hinge axis and positioned in said closure position opposite said surface for oppositely gripping therebetween a portion of said cord, said cam surface in said closure position being near

dead center, whereby an outwardly exerted pulling force on said cord will urge the cam further into cord gripping position, said cam in the release position of said cover being spaced from said surface sufficiently to release said cord, a contact terminal for each wire disposed on said body and protruding to the exterior thereof, and means connected to said cover and positioned in said closure position adjacent said terminals to press each wire into contact with a terminal.

7. In an electric connector, as claimed in claim 6, further characterized in that, said protrusions of said terminals including prongs at one side of the exterior of said body for removable connection to an electric outlet.

8. In an electric connector, as claimed in claim 7, in combination with, locking means including a latch positioned at said side of the body exterior carrying said prongs, and so arranged that said latch will be accessible only when the prongs are 20

removed off the electric outlet, whereby said cover will be restrained from movement away from said closure position during use of the connector.
